UNITED STATES PATENT OFFICE.

TRUMAN G. PALMER, OF CHICAGO, ILLINOIS.

GAS-BURNER.

1,253,091.

Specification of Letters Patent. Patented Jan. 8, 1918.

Application filed March 23, 1917. Serial No. 156,872.

To all whom it may concern:

Be it known that I, TRUMAN G. PALMER, a citizen of the United States, residing in the city of Chicago, county of Cook, and State 5 of Illinois, have invented certain new and useful Improvements in Gas-Burners; and I do hereby declare the following to be a full, clear, and exact description of the invention, such as will enable others skilled in 10 the art to which it appertains to make and use the same.

The invention relates to gas burners of the Bunsen type, such as are employed in connection with incandescent mantles, heating units and the like, and has for its object 15 to provide burners of this character with a simple and efficient means for applying and maintaining the foraminous diaphragms or wire gauze sections in proper relation in the mixing chamber to eliminate the noise or "roar" common to burners of this character 20 to insure a proper mixture of the gas and air, and to admit of the ready cleaning of or removal of the gauze sections.

25 The invention is illustrated in the accompanying drawings, in which:—

Figure 1 is a sectional elevation of a burner having the invention applied thereto;

Fig. 2 is a sectional elevation of the gauze-carrying thimble; and

Fig. 3 is a similar view of the burner cap.

Referring to the drawings, 1 indicates the burner tube upon which is removably supported a sleeve 2 carrying a mixing chamber 4, having at its top a telescoping cap 5 provided with a wire gauze diaphragm or strainer 5', constructed and arranged in accordance with standard practice.

In burners of this character, it is necessary to provide the mixing chamber with a foraminous diaphragm for the purpose of producing a proper admixture of the gas and air before the mixture is burned above the gauze cap, and to prevent the flame flashing back and igniting the gas at the base of the burner. Incidentally, also, the foraminous diaphragm, which is usually in the form of a wire gauze disk, serves to reduce the roar or noise which is characteristic of 45 Bunsen burners and which is objectionable when the burners are to be used for domestic purposes, such as lighting and heating. Various means for securing the gauze or foraminous diaphragm within the mixing 50 chamber have been devised, but, so far as applicant is advised, none of the prior de-

vices have proved entirely satisfactory, or efficient, for the reason that when one difficulty has been overcome, the organization, by means of which the result has been effected, gives rise to other objectionable effects and difficulties. It has been recognized that the foraminous diaphragm or gauze must be located in a definite part of the mixing chamber to produce the desired degree of 60 efficiency as to mixture, and when so located to accomplish this result, any derangement of the relative adjustment of the gauze results in an improper mixture and a noisy burner. The gauze is liable to become 65 clogged either by deposits from the gas, or by dust carried in with the air, which immediately impairs the efficiency of the device and requires careful cleaning to remove the dust and dirt from the gauze. In practically 70 all of the standard burners used for lighting purposes, it is customary to form one or more beads in the sheet-metal body of the mixing chamber to support the gauze, which latter is usually dished or flanged at its 75 edges and forced into position against one of the beads or between two of the beads. When this expedient is adopted, it is almost impossible to remove the gauze for cleaning purposes, or if successful removal can be 80 effected, it is difficult to replace the gauze 85 in proper position.

The present invention is designed to overcome all of these difficulties and to provide a simple form of device whereby the gauze 90 screen or screens will be properly located to effect a proper admixture of the air and gas, to completely eliminate the so-called roar or noise of the burner, and to admit of the parts being removed for cleaning the gauze 95 and replaced with absolute certainty of the parts being restored to their proper relations. To these ends, there is provided a sheet-metal thimble 7 provided with a reduced lower end which produces a shoulder 100 8 which is adapted to support the thimble on the bead or flange 6 which is ordinarily intended to support the gauze directly. The extreme lower end of the thimble is provided with an inturned flange 11 and the 105 extreme upper edge is finished with a slight upwardly turned flange 14 adapted to engage the upper edge of the mixing chamber 4 and support the thimble in proper relation in the chamber when the latter is not provided 110 with a bead, such as 6. It has been found advantageous to employ two screens of rela-

tively coarse mesh, in lieu of a single screen of fine mesh. The double screen arrangement effects a proper admixture of the air and gas, wholly eliminates the noise, and, further-
5 more, materially reduces the tendency of the gauze to become clogged with dust, dirt, or deposits from the gas. Such a double screen is shown in the drawings, the upper screen member being of a disk-like form resting
10 upon the shoulder 8 of the thimble and held accurately in position by means of a flanged metal ring 9. The lower screen member 12 rests upon the lower flange 11 of the thimble and is similarly held in position by means
15 of a flanged ring 13, the parts occupying the relative positions illustrated in Figs. 1 and 2, which, as will be seen, admits of the thimble with the double screen therein being removed bodily for the purpose of cleaning
20 the gauze of any accumulated dust or deposits. The upper edge of the thimble projects slightly above the upper marginal edge of the mixing chamber, so that the thimble can be readily engaged for removal, but will, under all conditions, be properly located in
25 the mixing chamber, whether the latter is provided with a supporting bead or not, inasmuch as the thimble will be supported by the bead 6 engaging the shoulder 8, or by
30 the upper edge of the mixing chamber engaging the flange 14, or by the engagement of both sets of supporting members. As indicated, the double screen, the individual members of which are of coarser mesh than
35 the ordinary single screen, not only reduces the tendency of the screens to clog, but admits of them being cleaned much more readily than a single fine mesh screen, and as the cleaning can be effected by removing
40 the thimble from the burner, the chances of

disturbing the proper location of the screen or screens are practically eliminated. If either of the screens is damaged, it may be readily removed and replaced with accuracy and facility, as will be apparent.

45

—What I claim is:—

1. An attachment for Bunsen burners comprising a tubular thimble having an outwardly flanged upper marginal edge adapted to engage the upper edge of the mixing chamber of the burner, a foraminous diaphragm carried by said thimble, and means for securing said diaphragm in position.

50 2. An attachment for Bunsen burners comprising a tubular thimble having an intermediate shoulder and a flange at its lower end, foraminous diaphragms supported by said shoulder and flange, and means engaging the interior of the thimble for securing the diaphragms in position.

55 3. An attachment for Bunsen burners comprising a tubular thimble having an intermediate shoulder and a flange at its lower end, foraminous diaphragms supported by said shoulder and flange, and rings engaging the walls of the thimble and serving to hold the diaphragms in position.

60 4. An attachment for Bunsen burners comprising a tubular thimble having an out-turned flange at its upper end, an inturned flange at its lower end, and a shoulder intermediate its ends, foraminous diaphragms supported on the intermediate shoulder and lower flange, respectively, and rings engaging the interior surface of the thimble and the respective diaphragms to hold the latter in position.

65 70 75 In testimony whereof I affix my signature.

TRUMAN G. PALMER.
